SWAB

Benjamin E. Parrish, Dallas, Tex.

Application November 19, 1934, Serial No. 753,709

4 Claims. (Cl. 103—225)

This invention relates to new and useful improvements in swabs.

One object of the invention is to provide an improved swab for wells which is adapted to be readily positioned on a cable at any point thereon without disconnecting said cable.

An important object of the invention is to provide an improved well swab having vertical tubular connectors extending therethrough, said 10 connectors not only serving to hold the parts of the swab together, but also providing passages for by-passing fluid when said swab is being lowered into a body of said fluid.

Another object of the invention is to provide 15 an improved swab for a well having vertical passages therethrough and also having flap valves at its upper end for closing said passages, the valves being mounted in pairs on a single mounting, whereby the cost of manufacture and the labor involved is greatly minimized.

A further object of the invention is to provide 20 a swab structure which is an improvement over my former patent, No. 1,788,738 issued January 13, 1931, and which is more easily and quickly 25 assembled and disassembled, whereby the clamping may be accomplished in much less time than is usually required.

Still another object of the invention is to provide 30 a swab including semicircular upper and lower members having an elastic swab element therebetween, and also including tubular connectors extending through said element, each connector having one end secured to one of the members and the opposite end extending through 35 the other member and receiving a nut, whereby the parts are held together and the swab element is capable of sliding on said connectors so as to permit expansion when the element is placed under pressure; the nut at the lower end 40 of each connector providing for quick assembling and disassembling of said parts.

A construction designed to carry out the invention 45 will be hereinafter described, together with other features of the invention.

The invention will be more readily understood from a reading of the following specification and by reference to the accompanying drawing, in which an example of the invention is shown, and wherein:

Figure 1 is a view, partly in elevation and partly in section of a swab constructed in accordance with the invention.

Figure 2 is a plan view, having a portion 55 broken away to show one of the valve mountings and also one of the fastening bolts,

Figure 3 is a horizontal, cross-sectional view, taken on the line 3—3 of Figure 1, and

Figure 4 is a transverse vertical sectional view of the upper supporting member.

In the drawing, the numeral 10 designates a 5 swab which is arranged to be positioned around the usual drilling cable A, and lowered into the casing B of an oil well. The swab includes an upper head 11 and a lower head 12. An annular flexible body 13 is disposed between the heads and 10 the outer face of this body is in constant engagement with the inner wall of the casing B. The heads are fastened together by vertical tubular connectors 14 which extend through the flexible body, as will be hereinafter explained. 15

The upper head 11 comprises a pair of semicircular plates 15, each of which is provided with an upstanding diametrically extending flange 16. The flange has its outer ends tapering upwardly so as to ride over obstructions, such as collars 20 and joints in the casing B, when the swab is raised therein. Each plate is provided with a semicircular cutout 17 at the center of its inner marginal portion, and when the plates are placed together, the inner faces of the diametrically extending flanges 16 lie against each other, as is shown in Figure 2. The semicircular cutouts 17 are in direct opposed relation, whereby a central vertical opening 18 is provided through the head. The drilling cable A passes through this opening, and bolts 19 threaded through registering bolt holes 19' in the flanges, securely fasten the plates together, as well as position the head around said cable. 25

A boss 20 is formed on the plate at the central 30 portion of the outer margin thereof, being preferably made integral therewith. The boss is provided with a bore 20' and one end of a transverse pin 21 is supported in this bore, while the other end of the pin is mounted in an aperture 22 at 35 the center of the vertical flange 16. A cotter key 21' passes through the boss and the pin to retain said pin in position. A reinforcing web 23 extends from the top of the boss 20 to the central portion of the flange 16, being positioned at 40 substantially a right angle to the longitudinal axis of the latter. The outer edge of the web is inclined toward the center of the head, similarly to the ends of the flanges 16 and the lower edge of said web is above the top edge of the 45 boss to permit flap valves 24 to be mounted to swing on the pin 21, as will be explained.

The lower head 12 is constructed similarly to the head 11, including semicircular plates 25, diametrically extending flanges 26 and a central 50

opening 27 for the cable. Bolts 19 pass through the flanges 26 to hold the plates 25 together. In the lower head 12, the bosses 20 are eliminated and a reinforcing web 28, similar to the web 23, 5 extends from each plate 25 to the flange 26, preferably being made integral with both plate and flange.

The flexible, annular body 13 is positioned between the heads 11 and 12 and has its upper and 10 lower ends engaged by the flat undersides of the heads. The body is constructed of two semicircular members 29, each having a vertical, semi-circular channel 30 at the center of its inner face. When the members are placed together with 15 their inner faces adjacent, the channels register to form a central vertical bore 31 through the body. With the body disposed between the heads, the bore 31 registers with the openings 18 and 27 in the heads 11 and 12, whereby the cable A 20 may pass downwardly through the swab.

In constructing the device, one of the members 29 of the body is secured between one of the plates 15 of the head 11 and one of the plates 25 of the head 12. This divides the swab into two 25 complete semicircular units which may be readily placed around the cable A. Since both units are assembled in the same way, a description of one will suffice.

The plate 15 is provided with two bosses 15' 30 which are positioned one on each side of the web 23, while the plate 25 is provided with similar bosses 25'. These bosses surround openings 32 in the plates and said openings register with elongated openings 33 which extend vertically 35 through the member 29. The tubular connectors 14 extend through the openings 32 and 33 and have their upper ends flared outwardly to securely fasten the same in the bosses 15' of the plate 15. It is pointed out that the upper end 40 of each connector is flush with the top of each boss 15' and this upper end is preferably machined to form a seat for the swinging flap valves 24. Each pin 21 has a pair of valves 24 pivoted thereto and the valves extend outwardly one from 45 each side of said pin as shown in Figure 2, to engage the bosses 15' when in a lowered position.

The lower end of each connector 14 is slidably mounted in and extends beyond the boss 25' and is threaded to receive a nut 34, whereby the 50 plates are connected with the member 29 therebetween.

It is obvious that the two units may readily be placed around the cable A and the bolts 19 inserted to fasten the units together. In positioning the swab, the lower end rests on any of the tools which may be secured to the cable and a clamp C is secured to the cable above the swab to prevent upward displacement of the same. Thus, it will be seen that the swab is incapable 60 of vertical movement. The tubular connectors not only connect the parts of each unit, but also serve as conductors for fluid to permit the bypassing of fluid when the swab is being lowered into the well.

65 In using the swab, the two semicircular units are positioned around the cable A, as has been explained. The clamp C is then secured above the swab and it is obvious that the swab is attached to the cable with a minimum amount of 70 time and labor, and since the device may be positioned at any point on said cable, the removal of any drilling tools connected to, or carried by the cable is not necessary. After the swab is positioned on the cable at the desired point, the 75 lowering operation is begun.

As the swab enters the body of fluid, the fluid passes upwardly through the connectors and raises the flap valves 24 which are pivoted on the pins 21. The upward swing of the valves is limited by stop 24' on said valves, striking the 5 webs 23. Thus, the fluid passes above the swab in the casing as the swab is lowered and so long as the lowering continues the valves remain open.

When the lowering of the swab is stopped and the swab is started upwardly, the weight of the 10 fluid immediately swings the flap valves 24 downwardly onto their respective seats at the upper end of the connectors, thereby preventing downward flow of fluid through said connectors. It is pointed out the upward swing of each valve 15 is limited by the stop 24' striking the web, so that the inclination of the valve when open is such that a pressure from above will immediately close said valve and any danger of swinging the valve past center to a wide open position is eliminated. Since the upper end of the connectors 14 are machined, a fluid tight joint is obtained and it is obvious that during the raising the oil above the swab is lifted. No leakage is had through the connectors and the engagement of the outer 25 face of the body 13 with the casing wall forms a fluid tight seal at all times. It is pointed out that since only the lower end of the connectors are fastened to the lower head, the upper ends being slidable through the upper head, the pressure above the swab forces the upper head downwardly to expand the packing element. This expansion forces the element outwardly into engagement with the casing wall, whereby a fluid 30 tight seal is affected.

When it is desired to remove the swab from the cable, it is only necessary to loosen the bolts 19 and the semicircular units will drop from the cable. The ease of mounting and dismounting the swab is an important feature of the device. 40 The particular arrangement of the connectors permits the same to not only serve as a connecting means between the heads 11 and 12, but also provides conductors for fluid during the lowering operation, as well as providing a mounting 45 for the packing element which permits expansion thereof when subjected to a pressure from above. By positioning the conductors on each side of the web 23, it is possible to pivot both valves 24 of each plate on the single pin 21. This 50 provides for a more compact as well as a much simpler device, which greatly reduces the cost of manufacture as well as the labor involved. The valves are positive in action with no danger of them not closing, and when seated on the bosses 55 15' a perfect fluid seat is maintained.

What I claim and desire to secure by Letters Patent is:

1. A split swab including, a pair of upper heads, a pair of lower heads, a split elastic body secured 60 between the heads, tubular connectors extending through the body and heads and having enlargements at each end for securing the upper and lower heads against separation, a single transverse pin mounted on each upper head, a pair of valves pivoted on the single pin and extending oppositely from each other, each valve closing the upper end of a connector, means for securing the two upper heads together, and means for securing the two lower heads together, 65 whereby the split elastic body forms a solid annular packing member.

2. A split swab including, an upper head split diametrically, a lower head split diametrically, a split elastic body having each of its sections 70

secured between one of the upper and lower heads, tubular connectors extending through the heads and body section and having enlargements on its ends for securing the heads against separation, a vertical flange extending upwardly from each section of the upper head, a single transverse pin mounted in each section of the upper head, valves hinged on the single pin for closing the upper end of the connectors, means for securing the flanges of the sections of the upper head together, and means for securing the sections of the lower split head together.

3. A split swab including, a pair of sections, each section comprising a substantially semi-circular upper head, a substantially semi-circular lower head, an elongate semi-circular elastic body secured between the heads, tubular connectors extending through the body and heads and having enlargements on their upper and lower ends for holding the heads against separation to retain the body therebetween, a single radial pin located centrally on the upper head, valves mounted on the single pin for closing the upper

end of the connectors, and means for securing the sections together, whereby an annular packing member is formed by the elastic bodies between the heads.

4. A split swab including, an upper head split diametrically, a lower head split diametrically, a split elastic body having each of its sections secured between one of the upper and lower heads, tubular connectors extending through the heads and body section and having enlargements on its ends for securing the heads against separation, a vertical flange extending upwardly from each section of the upper head, upstanding web extending from the side of each flange and having an opening therein, a single transverse pin fastened in the web and extending across said opening, valves hinged on the single pin for closing the upper end of the connectors, means for securing the flanges of the sections of the upper heads together, and means for securing the sections of the lower heads together.
